HAND LOOM

Karl L. Simons, Somerville, N. J., assignor of one-half to George H. Forrest, Somerville, N. J.

Application May 28, 1948, Serial No. 29,779

4 Claims. (Cl. 139—33)

1

The present invention relates to new and useful improvements in hand looms adapted for use in weaving various articles, such as small rugs or the like.

An important object of the invention is to provide a hand loom having a single heddle mechanism of simple construction and including a comb which operates to move alternately warp threads above and below the normal plane thereof to facilitate the passing of the woof or weft therethrough by means of the usual shuttle or needle and to further construct the comb with split rings or eyes to facilitate placing of the warp in the comb and removing the same therefrom.

Another object of the invention is to provide a heddle constructed for swinging the comb toward either end of the frame of the loom to facilitate working of the weft closely at the ends of the frame at the start and finish of the operation.

A still further object is to provide means for slidably adjusting the heddle bodily longitudinally of the loom to enable uniform raising and lowering movement of the warp throughout the length of the loom.

Another object of the invention is to provide a loom frame having a pivoted frame member at one end thereof to release the warp of the finished article when removing the same from the frame.

A still further object is to provide a device of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view;

Figure 2 is a side elevational view;

Figure 3 is an end elevational view with parts broken away and shown in section;

Figure 4 is a longitudinal sectional view taken substantially on a line 4—4 of Figure 1;

Figure 5 is a similar view showing the heddle swung downwardly for moving the warp below the normal plane thereof;

Figure 6 is a transverse sectional view taken substantially on a line 6—6 of Figure 2;

Figure 7 is a transverse sectional view of the pivoted end frame member showing the same swung inwardly for releasing the warp;

2

Figure 8 is an enlarged view in elevation of one of the eyes of the comb; and

Figure 9 is a side elevational view thereof and showing the bevelled entrance to the eye.

Referring now to the drawings in detail wherein for the purpose of illustration I have disclosed a preferred embodiment of the invention, the numeral 5 designates generally the loom frame which is preferably of polygonal shape to provide a pair of side frame members 6 and end frame members 7 and 8. The side frame members 6 and end frame member 7 are fixedly secured to each other in any suitable manner and end frame member 8 is pivoted for vertical swinging movement on a transverse rod 9 carried by the adjacent ends of the side frame member 6. A pair of locking pins 8a is provided for locking the pivoted end frame member 8 in its raised position. The upper edges of the end frame members 7 and 8 project upwardly above the side frame member 6 for a purpose more fully herein-after explained.

A plurality of hooks 10 and 11 are suitably secured to the upper edges of the end frame members 7 and 8 with the hooks projecting horizontally inwardly and to which the strands 12 of the warp may be attached and supported in spaced parallel flights between the hooks of the end frame members with end loops 12a on the warp 12 detachably attached, in any suitable manner, to the end frame member 8. Screw eyes 13 are positioned on the upper edge of the end frame members 7 and 8 adjacent the ends thereof and in which rigid rods 14 are removably supported in a position parallel to and in the plane of the warp 12. The rods 14 are positioned at each side of the warp and around which the woof or weft 15 is wound by means of the usual shuttle or needle 16 employed for feeding the woof transversely thereof.

Alternate flights or sheds of the warp 12 are raised and lowered by means of a heddle mechanism designed generally at 17 and comprising a substantially crank shaft construction to provide shafts 18 at each end of the heddle journaled in longitudinal slots 19 in the side frame members 6. Knurled knobs 20 are suitably secured to the outer ends of the shafts 18 to rock the latter for swinging the central crank portion 21 of the heddle vertically to raise and lower the same under the warp 12.

Coil springs 22 positioned on the end shafts 18 bear against the crank arms 23 and against washers 24 positioned on the shafts 18 at the

inner sides of the side frame members to hold the heddle against idle swinging movement.

The heddle 17 also includes a comb structure designated generally at 25 and comprising a plurality of rings or eyes 26 held in an upright position by shanks 27 rising from the crank portion 21 of the heddle. One side of each eye 26 is formed with an entrance slot 28 and with the opposed ends of the slotted eye inclined or bevelled as shown at 29 to smooth the entrance slot on one side of the eye as shown more clearly in Figures 8 and 9 of the drawings. Alternate flights or sheds of the warp 12 are inserted through the slots 28 for positioning in the eyes 26 and with the eyes freely slideable on the warp longitudinally of the frame 5.

In the operation of the device the warp 12 is anchored to the hooks 10 and 11 at each end of the frame 5 and with the eyes 26 of comb 25 carried by the heddle 17 engaging alternate flights or sheds of the warp. The heddle 17 is then rocked back and forth by the knobs 20 to raise and lower the sheds of the warp carried by the comb as shown in Figures 4 and 5 of the drawings to enable passing of the shuttle or needle 16 transversely thereof to thus feed the weft 15 through the warp and around the side rods 14. The elevation of the end frame members 7 and 8 facilitate manipulation of the shuttle or needle without interference by the side frame members 6.

The heddle 17 is swingable toward either end of the frame so that at the start of the weaving operation the sheds may be raised and lowered close to the starting end of the warp by sliding the heddle toward that end in the slot 19 and swinging the heddle toward the starting end of the warp to thus enable working of the weft close to the starting end of the article.

Likewise as the weaving approaches its finish or the opposite end of the frame the heddle 17 is moved longitudinally of the slot 19 and swung in a raising and lowering movement toward the finish end of the warp.

The springs 22 hold the shuttle in its slidably adjusted position as well as in its raised or lowered position.

After the weaving is completed the warp is released from the eyes 26 by sliding the same outwardly through the slots 28, the rods 14 are withdrawn from the ends of the weft 15 and the locking pins 8a withdrawn to permit the inward swinging movement of the end frame member 3 to release the warp from the hooks 10 and 11. The loops 12a may then be detached to free the finished article.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A hand loom comprising a frame including side frame members and end frame members, one of said end frame members being fixed, means

pivotedly connecting the other end frame member to the side frame members for inward swinging movement, warp attaching means carried by the end frame members to normally hold parallel warp threads taut in the frame, said warp threads being slackened by the inward swinging movement of the pivoted end frame member, and a combined heddle and comb for the warp threads, comprising a shaft rockably and slidably mounted in the side frame members and including a central crank portion, a warp engaging comb carried by said crank portion, and means holding the shaft in a rockably and slidably adjusted position in the frame comprising a spring frictionally holding the shaft in the frame.

2. A hand loom comprising a frame including side frame members and end frame members, one of said end frame members being fixed, means pivotally connecting the other end frame member to the side frame members for inward swinging movement, warp attaching means carried by the end frame members to normally hold parallel warp threads taut in the frame, said warp threads being slackened by the inward swinging movement of the pivoted end frame member, and a combined heddle and comb for the warp threads comprising a shaft rockably and slidably mounted in the side frame members, and including a central crank portion, a warp engaging comb carried by said crank portion, and means holding the shaft in a rockably and slidably adjusted position in the frame comprising a spring frictionally holding the shaft in the frame.

3. In a hand loom, a frame including side members, warp thread holding means on said frame, and a combined heddle and comb comprising a shaft rockably and slidably mounted in the side frame members and including a central crank portion, a warp engaging comb carried by said crank portion, and means holding the shaft in a rockably and slidably adjusted position in the frame comprising a coiled spring on the end of the shaft frictionally holding the shaft in the frame.

4. In a hand loom, a frame including side members, warp thread holding means on said frame, and a combined heddle and comb comprising a shaft rockably and slidably mounted in the side frame members and including a central crank portion, a warp engaging comb carried by said crank portion, and means holding the shaft in a rockably and slidably adjusted position in the frame comprising a coiled spring on the end of the shaft frictionally holding the shaft in the frame.
